UNITED STATES PATENT OFFICE.

FRANZ MORCHE, OF WYANDOTTE, MICHIGAN.

KNIFE-SHARPENER.

1,282,705.

Specification of Letters Patent.

Patented Oct. 22, 1918.

Application filed March 6, 1918. Serial No. 220,799.

To all whom it may concern:

Be it known that I, FRANZ MORCHE, a subject of Austria-Hungary, residing at Wyandotte, in the county of Wayne and State of Michigan, have invented certain new and useful Improvements in Knife-Sharpener, of which the following is a specification.

The invention provides simple and efficient means for sharpening knives, scissors, 10 cleavers, and kindred edged implements and tools which may be reduced to compact form and adapted to present a maximum amount of cutting edge for sharpening purposes.

15 The invention consists of opposed elements between which the article to be sharpened is adapted to have its edge portion drawn, said elements in the preferred form, being mounted upon a band or sleeve which 20 in turn is carried by a suitable support, such as a shank, pencil or like holder.

The invention also consists of a plurality 25 of blades pivotally connected at one of their ends and free at their opposite ends to swing laterally, or in a circle, so that any selected blade may be caused to occupy a position at one side or the other of the remaining blades, the angular spaces between the blades so positioned receiving the tool 30 or implement to be sharpened, said tool being drawn back and forth with its cutting edge in the angle formed between the blades, the latter operating to sharpen the tool by removing portions thereof upon opposite 35 sides.

For a full understanding of the invention and the merits thereof, reference is to be had to the following description and the drawings hereto attached, in which:—

40 Figure 1 is a side view of a tool embodying the invention, the dotted lines showing one of the blades moved so as to occupy a position at either side of the remaining blades.

Fig. 2 is an edge view of the sharpener.

45 Fig. 3 is a view similar to Fig. 2 showing a knife in position to be sharpened.

Fig. 4 is a side view showing the manner of using the device.

Corresponding and like parts are referred 50 to in the following description and indicated in all the views of the drawings by like reference characters.

The sharpener comprises a plurality of

blades 1 which may be of any construction or outline. As indicated, opposite end portions of the blade are reduced thereby leaving the intermediate portions prominently disposed for effective operation when in service. The blades are hardened so as to preserve their cutting edges and in practice, such blades will consist of tool steel properly tempered. Each of the blades has a handle 2 at one end formed by reducing a terminal portion thereof. A pivot fastening 3 connects the blades 1 at one of their ends, thereby admitting of any one of the blades being swung laterally or in a circle so as to occupy a position at one side or the other of the remaining blades, as indicated by the dotted lines in Fig. 1. The longitudinal edges of the blades are square thereby presenting four cutting edges. The angular spaces between the blades may be varied by spreading the free ends of the blades to a greater or less extent thereby 75 enabling every portion of the cutting edges of the blades being brought into operative position for service.

It will be understood from the foregoing, taken in conjunction with the accompanying drawings, that the invention provides a device of the character specified which is extremely simple in construction and effective in operation, and which when not required for immediate service, may be reduced to a compact form for convenience of carrying or storing. It is further noted that any number of blades may be employed in the formation of the device, the drawings illustrating three of such blades. When it is required to use the sharpener, one of the blades is swung laterally, or in a circle so as to occupy an angular position at one side or the other of the remaining blades. This is indicated by the full lines in Fig. 4, and by the dotted lines in Fig. 1. The knife 4, or other tool or implement to be sharpened, is placed in the angular space between the blades when separated with the edge facing the angle. The sharpening is effected by drawing the implement or tool backward and forward, portions being removed from opposite sides of the tool by the cutting edges of the blades. By separating the blades to a greater or less extent, every portion of the cutting edges thereof may be

brought into position for action, and moreover, the bevel to be given to the edge of the tool being sharpened may be regulated as will be readily understood.

5. What I claim is:

1. A sharpener, comprising a plurality of blades pivotally connected at one of their ends and separable at their free ends, any one of the blades being adapted to be moved laterally or swung in a circle so as to occupy a position at one side or the other of the remaining blades.
10. A sharpener of the character specified, comprising a plurality of blades having their end portions reduced, and their intermediate portions projecting to provide pronounced cutting edges, said blades being pivotally connected at one of their ends and adapted to be spread at their free ends either by a lateral movement or by being 20. swung around in a circle so that the blades

so moved may occupy a position at one side or the other of the remaining blades, the several blades when folded, occupying a position along the side of one another.

25

3. The herein described sharpener, comprising a plurality of like blades having their end portions reduced, and their intermediate edge portions projecting with their faces square across to provide four cutting edges, said blades being pivotally connected at one of their ends and free at their opposite ends to be swung laterally or in a circle, so that any one of the blades may occupy a position at one side or the other of the 30 remaining blades.

35

In testimony whereof I affix my signature in presence of two witnesses.

FRANZ MORCHE.
